Specification for Design.

Patented Aug. 30, 1921.

Application filed October 1, 1920. Serial No. 414,124. Term of patent 14 years.

To all whom it may concern:

Be it known that I, MARK CONSTANT COSGRAY, a citizen of the United States, residing at Sandusky, in the county of Erie and State of Ohio, have invented a new, original, and ornamental Design for an Electric Automatic Plant, of which the following is a specification, reference being had to the accompanying drawings, forming a part thereof.

Figure 1 is a side view, Fig. 2 is a front end view and Fig. 3 is a rear view of the electric automatic plant showing my new design.

I claim:—

The ornamental design for an electric automatic plant, as shown.

MARK CONSTANT COSGRAY.
